UNITED STATES PATENT OFFICE.

EDWARD E. JOHNSON, OF ST. PAUL, MINNESOTA.

SEWAGE SCREEN.

Application filed February 13, 1920. Serial No. 358,448.

To all whom it may concern:

Be it known that I, EDWARD E. JOHNSON, a citizen of the United States, residing at St. Paul, in the county of Ramsey and State 5 of Minnesota, have invented certain new and useful Improvements in Sewage Screens, of which the following is a specification.

My invention relates to sewage or water purification screens and an object is to provide a device of this character which may be readily constructed and installed and which will be efficient in operation. An object in particular is to provide a screen having a grating and a comb which are adapted to be moved relatively to each other with the teeth of the comb extending through the spaces in the grating whereby clogging thereof is prevented.

The full objects and advantages of my invention will appear in connection with the detailed description thereof and the novel features embodied in my inventive idea will be particularly pointed out in the claims.

In the accompanying drawings, which 25 illustrate the application of my invention in one form,—

Fig. 1 is a view in vertical section on the line 1—1 of Fig. 2. Fig. 2 is a view in vertical section on the line 2—2 of Fig. 1. Fig. 30 3 is an enlarged detail view in vertical section through the grating and comb, the section through the grating being on the line 3—3 of Fig. 1 with the comb moved into this position. Fig. 4 is a section on the line 35 4—4 of Fig. 3. Fig. 5 is a fragmentary sectional elevational view showing the manner in which the comb is cleaned. Fig. 6 is a detailed view showing the attachment of the upper ends of the comb teeth and omitting 40 the grating.

Referring to the construction shown in the drawings, I provide a flume 10 preferably of concrete for conducting away the sewage after it has passed through a screen grating 45 which removes the coarse material. The sewage is admitted above the grating by a pipe 12 and is maintained at about the level indicated at α by any customary or suitable means, as by a float valve of well-known 50 construction which it is not necessary to illustrate for the purpose of explaining my invention. The screen is of concave or cradle form and is supported by curved longitudinal bars 14 which are held together by tie rods 16. Transverse bars 18 rest upon the curved bars 14, and as shown in Fig. 3 the transverse bars are received in notches in the curved bars. The grating which constitutes the screen proper is cylindrically curved for as much of the surface of a cylinder as desired and consists of a plurality of curved T-shaped members 20, as shown in Fig. 3, having their head portions arranged in curved alignment with each other and spaced slightly apart and having their stem 60 portions resting in sockets formed in the upper ends of a multiplicity of plates or lugs 22 the lower ends of which are secured in the transverse bars 18. The plates or lugs 22 have a width substantially equal to the thickness of the transverse bars 18 and said plates are preferably formed by doubling metal strips in the middle and offsetting the free ends to form the sockets for receiving the 65 stems of the T bars, which may be secured in place by spot welding. The plates or lugs 22 are of sufficient height to support the whole of the T bars 20 above and free from the transverse bars 18 to provide clearance for comb teeth which will be described 70 later. The spaces or slots 20^a between the T bars are thus completely free longitudinally for the entire length of the T bars and in depth are free from the top of the T bars to the top of the transverse bars 18. The 75 ends of the curved longitudinal bars 14 are supported upon angular bars 24 and the sides of the cradle structure are closed by plates 26. Rubber strips 28 resting upon the transverse bars 18 abut upon the plates 26 80 and provide a tight closure at the sides of the receiving basin which is formed above the grating. The inlet pipe 12 terminates adjacent a hole in one of the plates 26 and is screw-threaded into a collar 30 bolted to the 85 plate. Longitudinal angle bars 32 serve to support a framework 34 which at its top has bearings 36 for a rock-shaft 38 to which is secured a crank arm 40 connected by a link 42 to a shorter crank arm 44. The latter 90 crank arm is secured to a shaft 46 mounted in a bearing 48, and a belt pulley 50 is secured to the shaft 46 for rotating the same from any suitable source of power. The rock-shaft is positioned at the center of 95 curvature of the screen and to this shaft are secured arms 52 having a bar 54 bolted to the lower ends thereof. This bar carries a comb which consists of teeth 56 between which are secured strips of rubber 58 which 100 yieldingly support the teeth. The rubber strips are shorter than the teeth and the free 105 110

ends of the latter are of sufficient length and are properly spaced so as to extend through the spaces between the heads of the T members 20. The comb teeth 56 are preferably made of thin material, in order to move freely in the narrow openings or slots 20^b between the T bars 20 and they accommodate themselves to any slight irregularities of the path thru which they are swept at each reciprocation of the bar 54. The teeth 56 have preferably a considerable width as measured along the slots 20^b so as to be of sufficient strength to carry the solid matter which they collect as they sweep forward. They are preferably formed with curved edges as shown in Figs. 1 and 5. Applicant is aware that certain constructions have been made for cleaning grates of debris where a comb enters and leaves grating slots in its operation. When however it is desired to screen fine solids, greater refinement of construction is necessary and in order to guard against wrecking the apparatus, I do not allow the comb to leave the slots in which it operates. The operating connections for the rock-shaft are so proportioned and arranged that the comb is given an oscillatory movement end to end of the screen with the teeth of the comb constantly maintained in the spaces between the T members. These teeth remove coarse material which will not pass through the screen and carry it to one end or the other thereof and deposit it in troughs or receptacles 60. The active or wet screen 35 is that portion lying below the level α which is kept well below the ends 20^c of the screen so as to leave dry the portions of the screen from 20^b to 20^c. The comb in its forward movement having traversed the wet portion 40 of the screen carries its load of solids across the dry portion allowing an appreciable draining thereof before these solids are ejected as will be later described. In order to clean the comb and facilitate the deposit of the coarse material in the troughs the following device is provided at each end of the screen. Brackets 62 are provided with bearings for a shaft 64 to which is secured a belt pulley 66 which is driven from any suitable 45 source of power for rotating the shaft. Secured to said shaft are arms 68 to the outer ends of which are secured blades 70 of a revolving cleaner which move in proximity to the teeth of the comb when the latter is in its outward position at the ends of the screen.

The operation and advantages of my invention will be readily understood from the foregoing description. The employment of a plurality of T-bars having their head portions placed in juxtaposition and slightly spaced from each other provides an efficient grating which may be conveniently supported by means of the stem portions of the T-bars. The lower edge 56^a of the comb teeth 56 extends well below the bottom edge of the

T bar grating as shown in Figs. 3 and 4. The teeth of the comb on account of extending through the spaces in the grating prevent clogging not only by removing coarse material which lodges on top of the grating, but also by removing material which lodges in the spaces between the grating members. Since the teeth of the comb are constantly maintained in the spaces between the grating members there is no liability of the teeth failing to cooperate properly with the grating in the spaces for which they are intended. The rubber strips between the teeth permit lateral movement of the latter so that they are readily accommodated to any irregularities in the grating members. The supporting bars 14 are notched at their ends as shown in Fig. 1 to rest upon the angle bars 24 and hence the grid or screen structure may be removed bodily for repairs. The plates 22 hold the T-bars above and away from the crossbars 18 and allow slight lateral movement of the T-bars to adjust them to the comb and to allow the teeth of the comb to run completely between and below the members of the grating in order to open up through grease which in some climates collects upon and below the screen surface.

My screen is intended particularly for use as a sewage screen but it will be understood that it is adapted for general use as a water purification screen.

I claim:

1. A water purification screen comprising a grating, a comb having teeth extending thru the slots in the grating, resilient means interposed between the base portions of said teeth, and means for moving said grating and comb relatively to each other while constantly maintaining said teeth in said slots.

2. A water purification screen comprising a curved grating, a rock-shaft positioned at the center of curvature of said grating, a comb attached to said rock-shaft and having teeth extending thru the slots in said grating, and means for rocking said shaft to cause said comb to oscillate from end to end of said grating.

3. A water purification screen comprising a curved grating, a comb having teeth extending thru the slots in said grating, means for oscillating said comb from end to end of said grating, and means at the ends of said grating for cleaning said comb.

4. A water purification screen comprising a curved grating, a comb having teeth extending thru the slots in the grating, means for oscillating said comb from end to end of said grating, and rotatable cleansers mounted at the ends of said grating adapted to rotate in proximity to the comb when the latter is in its extreme outward positions.

5. A water purification screen comprising a curved grating, a comb having teeth extending thru the slots in the grating, means

- for oscillating said comb from end to end of said grating, receptacles at the ends of said grating, and rotatable members above said receptacles, said rotatable members having slots, a comb having teeth extending thru the slots in said grating, and means for moving said grating and comb relatively to each other. 25
- 5 blades which sweep the comb when the latter is in its extreme outward positions.
6. A water purification screen comprising a curved grating, a comb having teeth extending thru the slots in said grating, 30 resilient means interposed between the base portions of said teeth, and means for oscillating said comb from end to end of said grating.
7. A water purification screen comprising a curved grating having bars, curved supporting bars underneath said grating and concentric with the bars thereof, and transverse bars extending between said grating and said supporting bars and resting 35 upon the latter.
- 15 8. A water purification screen comprising a plurality of cylindrically curved T bars supported side by side and spaced from each other to form a grating having open ended
9. A water purification screen comprising a plurality of screen elements mounted in spaced parallel relation, outstanding lugs attached to said elements at intervals, and a plurality of transverse supports to which said lugs are fastened whereby said elements are supported as separate units. 40
10. A water purification screen comprising a grating made up of a plurality of screen elements mounted in spaced parallel relation to form slots extending the full length of the grating and open at both ends thereof, outstanding lugs attached to said elements at intervals, and a plurality of transverse supports to which said lugs are fastened. 45

In testimony whereof I hereunto affix my signature.

EDWARD E. JOHNSON.
